United States Patent Office.

WILLIAM MAROT MARSHALL, OF PHILADELPHIA, PENNSYLVANIA.

Letters Patent No. 79,667, dated July 7, 1868.

IMPROVED AIR-CARBURETTER.

The Schedule referred to in these Letters Patent and making part of the same.

Be it known that I, WILLIAM MAROT MARSHALL, of Philadelphia, in the county of Philadelphia, in the State of Pennsylvania, have invented a new and useful Improvement in Air-Carburetters; and I do hereby declare that the following is a full, clear, and exact description thereof, reference being had to the accompanying drawings, and to the letters of reference marked thereon, making a part of this specification, in which—

Figure 1 represents, in perspective, a view of the bellows and carburetter attached.

Figure 2 represent a longitudinal vertical section of the carburetter.

Figure 3 represents, in perspective, a view of a cone, formed of metal tube, to be attached to the carburetter as an air-heater.

Similar letters of reference denote like parts where they occur in the several figures, in which

A is the bellows.

B C is the carburetter.

D is a small telescopic gasometer attached to carburetter.

E is a cone, of coiled metal tub, attached to carburetter.

F is a small gas-pipe, with stop-cock and burner.

G is that portion of the cone E which passes into carburetter.

H is that portion of the cone E which is attached to bellows.

I represents carburetted air.

K represents hydrocarbon-fluid.

L is the tube leading carburetted air into the gasometer.

M is the tube conducting carburetted air to pipes and burners.

O is the supply-pipe.

R is the funnel of supply-pipe.

S is a jet of ignited carburetted air burning within the cone E.

W represents water in the gasometer.

P P are the pans holding hydrocarbon-fluid.

The nature of my invention consists in connecting any suitable bellows, blower, or pump, with any suitable air-carburetter, by means of a coiled copper or other metal tube, formed into a cone or other shape, so as to present a large heating-surface to a flame of carburetted air burning within its folds. By this means the air passing from the bellows to the carburetter must necessarily pass through a considerable length of highly-heated pipe, and thus become sufficiently heated to promote a complete volatilization of the hydrocarbon-fluid contained in the pans of the carburetter, and working with the same certainty in winter as in summer.

To enable others skilled in the art to make and use my invention, I will proceed to describe its construction and operation.

I coil a piece of copper tube in any suitable shape which will present a large portion of its external surface to the direct action of a jet of flame. I prefer coiling it in the shape of a cone, as seen in fig. 3, which shape is best adapted to present the largest amount of surface to the flame S, as seen in fig. 2. The upper end, H, of this coiled tube, I attach to the vent of the bellows A, as seen in fig. 1, and the lower end, G, I pass through a hole in the lid of the carburetter, and through or around the pans, until its lower mouth is in a position to discharge the air, (which has been heated in passing through it,) into or upon the surface of the hydrocarbon-fluid in the lowest apartment of the carburetter, and passing on in the direction of the arrows, (as seen in fig. 2,) until it reaches the upper apartment, when it passes by the tube L into the gasometer D, and, following the direction of the arrows, is forced through the tube M to supply the various pipes and burners to which it is attached. For this purpose I attach a small gasometer, (see D, figs. 1 and 2,) to the top of the lid of the carburetter. I also insert a pipe, F, fig. 2, through the lid of the carburetter. This pipe is provided with a stop-cock, and a burner on its end, which is turned up in such a manner as to jet the flame S with the folds of the cone E.

This flame is supplied by carburetted air, drawn directly from the carburetter, and is made to branch in many directions by numerous slits crossing each other in the tip of the burner.

For the purpose of supplying the carburetter with hydrocarbon-fluid when needed, I insert into one end, or some other suitable part of the carburetter, the end of the pipe of a safety-feeder, constructed as follows: I make a globular chamber, of metal, (see O, fig. 2,) which will hold sufficient fluid for one feeding. To the lower part of this chamber I attach a tube, with stop-cock, and at the upper part of the chamber I attach a funnel, R, and stop-cock. If the cock N be closed, and the cock T be opened, the fluid, K, poured into the funnel R would soon fill the chamber O. Then, if the cock T be closed, and the cock N be opened, the fluid, K, will pass into the carburetter.

Having described my invention, I will endeavor to describe some of its advantages.

It will volatilize the hydrocarbon-fluid in cold weather as well as in hot, which feature is deficient in most of the carburetters in use.

With my improvement a lower grade of hydrocarbon-fluids may be used with better success than can be obtained with high-grade fluids in cold-air machines.

Any number of carburetters may be attached by means of my invention to a continuous pipe leading out from one bellows, so that a whole block of buildings might be supplied by one bellows sending air to a separate carburetter in each house, thus cheapening the expense to each consumer, and insuring a brighter and more economical light than can be obtained in coal-gas.

What I claim as my invention, and desire to secure by Letters Patent, is—

1. The coiled copper or other metallic pipe, E, substantially as described and for the purpose set forth.
2. The coiled pipe E, in combination with pipe F and flame S, and with the blower A and carburetter B C, when connecting the blower with the carburetter, substantially as and for the purpose set forth.
3. The feeder R O, with its chamber O, funnel R, stop-cocks N and T, and its pipe, substantially as and for the purpose set forth.

WILLIAM MAROT MARSHALL.
